[57] CLAIM

The ornamental design for a clinical analyzer, as shown and described.

DESCRIPTION

FIG. 1 is a front elevational view of a clinical analyzer, showing my new design;

FIG. 2 is a top plan view thereof the bottom plan view being plain and unornamented;

FIG. 3 is a right side elevational view thereof;

FIG. 4 is a left side elevational view thereof; and,

FIG. 5 is a rear elevational view thereof.

The broken line showing of the details in FIG. 2 is for illustrative purposes only and forms no part of the claimed design.

FIG. 1
